By Attorney

Aaron L. Appelbaum

UNITED STATES PATENT OFFICE.

NATHAN MILLER, OF BROOKLYN, NEW YORK, ASSIGNOR OF ONE-HALF TO HYMAN LEHMAN, OF BROOKLYN, NEW YORK.

FUR STRETCHER.

Application filed February 15, 1926. Serial No. 88,383.

This invention relates to fur stretching devices and has for its object to provide a novel and improved construction attachable to a wall, work bench or table in such manner that the said device may be caused to expand to stretch the skin or fur being prepared.

One of the objects of my invention is to provide a fur stretching device particularly designed for the smaller skins of animals, although it is equally applicable for larger skins, in which but slight pressure is required to cause the stretcher to expand the skin or fur being handled.

Another object of my invention is to construct a fur stretching device of the character above specified and more particularly of the lazy-tong type, associated with and cooperating with a bracket so that when the skin is placed on the stretcher, as the operator presses the device downwardly, the sides of the stretcher are caused to expand and when the pressure is released, the sides close in proximity to each other permitting the fur or skin to be quickly removed and thus facilitating the work thereon.

In order to more fully understand and appreciate my invention, reference is had to the accompanying drawing showing a preferred embodiment thereof in which

Fig. 1 is a plan of the stretcher and bracket.

Fig. 2 is a side view.

Fig. 3 is a plan showing the stretcher in its open position.

Fig. 4 is a side view showing the stretcher in its open position.

Fig. 5 is a sectional view taken on the line 5—5 of Fig. 3.

Fig. 6 is a slightly modified form of stretcher showing the end stretcher members for the head and jaws of the fur.

Fig. 7 is a sectional view taken on the line 7—7 of Fig. 4.

Referring now to the drawings wherein like reference characters designate corresponding parts throughout the several views, 5 designates the base and 6 the rear wall of a bracket which may be secured or attached

in any suitable manner to a wall, work bench or table for the convenient operation of the worker. The bracket is provided with an overhanging top portion 7 to the end of which is pivotally connected as at 8, the stretcher carrying support or plate 9, said

plate being substantially L-shaped in cross section and its bottom portion 10 curved or flared outwardly as suggested by Figs. 1 and 3 of the drawing.

The stretcher proper consists of a pair of parallel side bars 11, 12 which are substantially U-shaped in cross section, said bars being formed so as to taper uniformly and gradually toward their ends 13. The opposite ends of the said bars are pivotally connected to the bottom portion 10 of the plate by suitable links 14 and fastened to the said bars by studs or rivets 15.

The plate 10 is further provided with a suitable guide 10^a on its bottom face for the rear end 16 of a spreader 17 longitudinally movable between the bars 11, 12. The sides of the said bars 11 and 12 are each provided with longitudinal slots 18 for a transversely extending pin 19 passing through the spreader 17 which guides the forward end thereof. Suitable links 20, 21 are pivotally connected to the spreader and to the side bars 11, 12, thus producing a lazy tong type stretcher.

The opposite end of the spreader 17 is provided with a cam shaped or curved head 23 which is adapted to slide on the curved inner face 22 of the bracket. A resilient element, preferably a coiled spring is positioned on the spreader between the curved head 23 and the back wall of the L-shaped plate as indicated by numeral 25. The spring normally maintains the side bars and spreader closed and contiguous to each other as shown by Fig. 1 of the drawing. In this position, when a fur or skin is placed on the stretcher, as the operator depresses the plate 10 against the resistance of the spring, the spreader is urged outwardly, thus separating the side bars through the connecting links to the position shown by Fig. 3.

It will be thus seen that the side bars may be spread to varying degrees determined by the amount of pressure exerted, it being understood that the worker will use his best judgment in the handling of the fur as to how much stretching is desired. As the pressure is released, the spreader automatically moves inwardly, thus closing the stretcher to the condition shown by Fig. 1.

In Fig. 6 I have shown the side stretcher bars 11, 12 provided with end stretching members in the form of two links 26, 27 pivotally connected as at 28 to the said ends so as to open therewith. The links 26, 27

cross and are pivotally connected at 29, terminating in jaws 30 which are adapted to enter the head of the fur being treated. This form of the invention is utilized in the 5 larger type of furs, the side bars, pusher rod and spreader operating in conjunction with the plate 10 in the same manner as described in connection with Figs. 1 and 3.

Having shown and described my invention 10 what I now claim as new and desire to secure by Letters Patent of the United States is:

1. A stretcher of the class described comprising a support, a resiliently held pivoted member connected to the support, a pair of side bars connected at one end to the pivoted member, a spreader carried by the said member and connected to the side bars whereby the said bars are moved outwardly relatively 20 to each other when the spreader is actuated longitudinally.

2. A stretcher of the class described comprising a support, a pivoted member connected to the top of the support, a pair of 25 side bars and links connecting said bars to the pivoted member and a longitudinally movable spreader located between the side bars for separating the same when pressure is applied to the pivoted member.

3. A stretcher of the class described comprising a support, a pivoted member connected to the support, a pair of side bars and links connecting the bars to the pivoted member, a spreader located between the side 35 bars, links connecting the spreader to said bars, the rear end of said spreader being adapted to engage the support when pressure is applied to the pivoted member whereby the said spreader is movable longitudinally and the side bars outwardly.

4. A stretcher of the class described comprising a support, a pivoted member connected to the support, a pair of parallel side bars and end links connecting the same to the pivoted member, a spreader and guiding 45 means on the pivoted member for the spreader, links connecting the spreader to the side bars, a transverse pin extending through the side bars and one end of the spreader, the opposite end of the spreader having resilient means adapted to engage

the support whereby said spreader is moved longitudinally and the side bars relatively to each other.

5. A stretcher of the class described comprising 55 a support, an L-shaped member pivoted to the support, a pair of side bars and links connecting the ends of the side bars to the pivoted member, a spreader T-shaped in cross section carried by the pivoted member and extending between the side bars, links connecting the spreader with the said bars, a transverse pin carried at the outer end of the spreader and passing through slots in the side bars, the opposite end of the spreader having a head and resilient means engaging the support whereby the spreader is actuated longitudinally to move the side bars as pressure is applied to the said pivoted member.

6. A stretcher of the class described comprising a support, a pivoted member connected to the support, a pair of movable bars and a spreader located between the said bars, links connecting each of the bars and spreader with each other, links connecting the ends of the bars with the said pivoted member, resilient means at one end of the spreader for normally maintaining the bars in contiguous relation in one position, said bars being movable outwardly relatively to each other when the pivoted member is depressed.

7. A stretcher of the class described comprising a support, a pivoted member connected to the support, a pair of side bars tapering toward one end thereof and having links connecting the opposite ends to the pivoted member, a T-shaped spreader bar between the side bars, links connecting the spreader bar with the side bars, resilient means on the spreader between the pivoted member and support, for normally maintaining the side bars in contiguous relation to each other, a transverse pin extending through the opposite end of the spreader and movable in longitudinal slots in the side bars, and means for guiding the spreader in its longitudinal movement to spread the side bars as the pivoted member is depressed.

In testimony whereof I affix my signature.
NATHAN MILLER.
